[57] CLAIM

The ornamental design for an automobile wheel, substantially as shown and described.

DESCRIPTION

FIG. 1 is a side elevation view of the automobile wheel showing my new design;

FIG. 2 is an end elevation view thereof;

FIG. 3 is a side elevation view thereof taken from the side opposite to that of FIG. 1; and

FIG. 4 is an enlarged cross sectional view thereof taken along the line 4—4 in FIG. 1

FIG. 5 is a side elevation view of the automobile wheel showing a second embodiment of my new design;

FIG. 6 is an end elevation view of FIG. 5;

FIG. 7 is a side elevation view of the side opposite to that shown in FIG. 5; and

FIG. 8 is an enlarged cross sectional view taken along the line 8—8 in FIG. 5.
